UNITED STATES PATENT OFFICE

SAMUEL RUBEN, OF NEW ROCHELLE, NEW YORK

REMOTE CONTROL DEVICE

Application filed October 24, 1929. Serial No. 402,294.

This invention relates to an apparatus and method for obtaining remote control of a movable system. It is an adaptation in part of the system described in my prior and co-pending applications Serial Numbers 387,593 and 387,594 filed on the 22nd day of August, 1929; specifically this application relates to a method of and apparatus for effecting the movement of and controlling a rotary motion system.

An object of the invention is to provide a remote control device, controllable by pressure resulting from the electrolysis of a solution with facilities for quickly releasing the pressure. Other objects will be apparent from the disclosure.

Primarily, the invention is designed to obtain control of a rotary motion apparatus, for example, whereby devices such as the tuning condensers of radio set are rotated to desired positions by operation of the system at a distance or whereby the arms of semaphores, or valves or switches and switch systems are operated from a distance.

In this invention, the pressure developed by electrolysis, is utilized as the operating force in the remote control system and the recombination of the gaseous product, together with a self restoring means, such as a spring, are used to return the controlled device to its original position.

The device can be best described by reference to the accompanying drawing showing a desirable arrangement, wherein (1) is a piston chamber in which piston (2) fits; (3) is a spring for keeping piston under force toward end of cylinder; (4) is an end bearing; (5) is a rack and (6) a pinion gear arranged so that when rack (5) is pushed outward by piston (2) it will rotate the pinion gear which is coupled to the device which it is desired to controllably rotate or move, for example, the rotary moving tuning condenser of a radio set, etc.; (7) is the electrolysis chamber in which is contained electrolyte of caustic soda (7a); (8) and (9) are electrodes; where the potential is direct current, both electrodes can be of lead; where alternating current is used, one should preferably be of lead and the other of tantalum or other rectifying ma-

terial; (10) is a platinum wire coil supported on insulating bushing (11); (12) and (13) are terminals connecting the electrode to the source of potential (15) through a single pole double throw switch as composed of lever (16) and contacts (17) and (18).

In operation, when lever (16) is in contact with (17), the electrodes (8) and (9) are energized; the electrolysis of solution (7a) occurs and the pressure of electrolysis causes piston (2) to be forced out which causes the pinion gear (6) to be rotated by virtue of the power exerted on piston (2). The spring (3) is compressed when the piston (2) is moved out as far as is desired and when a return movement is desired, the switch lever is connected to contact (18) which connects the platinum heater coil (10); as oxygen and hydrogen, combine immediately in the presence of a heated platinum wire, there is a conversion into water which drops back into the electrolyte (7a). The reduction of pressure due to the combination of the gases causes piston to assume its normal position and this is assisted by tension of spring (3). By regulation of the current density applied to either electrolyzer or recombiner, the respective motion rates can be controlled.

The electrolysis chamber may be made of insulating material or itself be a conductive body such as iron and used as one of the electrodes. The electrolyte solution may be caustic soda or other solutions.

A diaphragm type bellows can be used to transmit the pressure instead of the piston.

What is claimed is:

1. A system for obtaining a rapid remote control which comprises the combination of an electrolytic chamber containing electrodes and a solution capable of rapidly giving off oxygen and hydrogen when electrolyzed, a piston chamber connected to said electrolytic chamber and housing a piston movably responsive to the pressure generated in said chamber and adapted to control the movement of an exterior rotary motion device, a heater wire to recombine the generated gases located within said electrolytic chamber, and means for selectively energizing the elec-

trodes of said electrolytic chamber or the said heater wire.

2. A system for obtaining a rapid remote control which comprises the combination of 5 an electrolytic chamber containing electrodes and a solution capable of rapidly giving off oxygen and hydrogen when electrolyzed, a piston chamber connected to said electrolytic chamber and housing a piston movably responsive to the pressure generated in said

chamber and adapted to control an exterior movable element, a heater element to recombine the generated gases located within said electrolytic chamber, and means for selectively energizing the electrodes of said electrolytic chamber or the said heater element. 70

Signed at New York in the county of New York and State of New York this 23rd day of October A. D. 1929.

SAMUEL RUBEN.
